UNITED STATES PATENT OFFICE

166,812

CLEANER AND SCRAPING UNIT

Samuel Lustbader, Brooklyn, N. Y.

Application August 1, 1951, Serial No. 16,100

Term of patent 3½ years

(Cl. D62—2)

To all whom it may concern:

Be it known that I, Samuel Lustbader, a citizen of the United States, residing in Brooklyn, county of Kings and State of New York, have invented a new, original, and ornamental Design for a Cleaner and Scraping Unit, of which the following is a specification, reference being had to the accompanying drawing, forming a part thereof, wherein:

Fig. 1 is a top plan view of a cleaner and scraper unit embodying my new design;

Fig. 2 is a side elevation thereof;

Fig. 3 is an edge view of the same; and

Fig. 4 is a fragmentary vertical section taken along lines 4—4 of Fig. 1 in the direction of the arrows as indicated in that figure.

The nozzle head illustrated in Fig. 2 has been omitted in the showings in Figures 1 and 3 for

convenience of illustration. The side of the unit opposite to that shown in Fig. 2 is substantially like the side illustrated in that figure.

The dominant features of my design are shown in full lines.

I claim:

The design for a cleaner and scraping unit, substantially as shown and described.

SAMUEL LUSTBADER.
